US0D1023024S

(12) **United States Design Patent** (10) Patent No.: **US D1,023,024 S**
 Machniewska (45) Date of Patent: ** Apr. 16, 2024

(54) **DISPLAY SCREEN WITH GRAPHICAL USER INTERFACE**

(71) Applicant: **Click Therapeutics, Inc.**, New York, NY (US)

(72) Inventor: **Gosia Machniewska**, New York, NY (US)

(73) Assignee: **Click Therapeutics, Inc.**, New York, NY (US)

(**) Term: **15 Years**

(21) Appl. No.: **29/764,121**

(22) Filed: **Dec. 28, 2020**

(51) **LOC (14) Cl.** **14-04**

(52) **U.S. Cl.**

USPC **D14/485**

(58) **Field of Classification Search**

USPC D14/485-495

(57) **CLAIM**

The ornamental design for a display screen with graphical user interface, as shown and described.

DESCRIPTION

The FIGURE is a front view of a display screen with graphical user interface showing the new design.

The broken lines showing an electronic device illustrate environmental subject matter and form no part of the claimed design. The remaining broken lines showing elements of the graphical user interface illustrate portions of the article and form no part of the claimed design.

1 Claim, 1 Drawing Sheet
